US0D1100034S

(12) **United States Design Patent** (10) Patent No.: **US D1,100,034 S**
(45) Date of Patent: ** Oct. 28, 2025

(54) **CALCULATOR**

(71) Applicant: **Guangzhou Cania Technology Co., Limited**, Guangzhou (CN)

(72) Inventor: **Zhensui Zheng**, Guangzhou (CN)

(73) Assignee: **Guangzhou Cania Technology Co., Limited**, Guangzhou (CN)

(**) Term: **15 Years**

(21) Appl. No.: **30/015,149**

(22) Filed: **Jul. 27, 2025**

Related U.S. Application Data

(63) Continuation of application No. 29/960,817, filed on Sep. 3, 2024, now abandoned.

(30) **Foreign Application Priority Data**

Jun. 11, 2024 (CN) 202430352774.5

(51) **LOC (15) Cl.** **18-01**

(52) **U.S. Cl.**

USPC **D18/7**

(58) **Field of Classification Search**

(57) **CLAIM**

The ornamental design for a calculator as shown and described.

DESCRIPTION

FIG. 1 is a front perspective view of a calculator, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view.

The broken lines in the drawings illustrate the portions of the calculator, which form no part of the claimed design.

1 Claim, 7 Drawing Sheets
